Application filed March 25, 1931. Serial No. 39,239. Term of patent 7 years.

To all whom it may concern:

Be it known that I, PERCEVAL S. The figure is a plan view of a textile fabric or similar article showing my new design. A single unit of my design is substantially

comprised within the area defined by the indicating dotted lines on the drawing.

The leading feature of my design consists in partiallylapping representations of backgammon boards spaced on the fabric. Representations of accessory devices are provided in the spaces between the backgammon boards.

I claim:

The ornamental design for a textile fabric or similar article substantially as shown and described.
